UNITED STATES PATENT OFFICE.

HENRY M. GREEN, OF LOS ANGELES, CALIFORNIA; PACIFIC SOUTHWEST TRUST & SAVINGS BANK, ADMINISTRATOR OF SAID HENRY M. GREEN, DECEASED, AS SIGNOR TO C. M. O'LEARY.

GAS EXTRACTOR FOR PUMPS.

Application filed July 20, 1925. Serial No. 44,852.

This invention relates to pump intakes and especially to the intakes of deep well pumps where the liquid being drawn is impregnated with gas bubbles minute to large sizes.

5 When pumping oil wells, natural gas flows into the pump intake and when collecting in large volumes under the pump valves tends to hold the valves up from the seats and therefore prevents any uplift of the oil in 10 the suction pipe or pump anchor so long as the gas body fills the chambers in the pump.

15 My present invention is designed to first reject as much of the gas as possible from the oil passing into the lowermost mouth of the pump, then to break up such gas bubbles as may collect or form in the intake, then to 20 separate the reduced bubbles from the oil in transit in the intake means and then vent off the gas from the intake pipe, back to well space outside of the pipe intake line.

25 In accomplishing this object I employ a unit comprising a gas rejector, a gas bubble breaker, a gas and oil separator, a gas trap, and a vent. According to well conditions a system of the units may be arranged entrain.

30 An object is to provide means for accomplishing the separation of the gas from the oil without the employment of any movably operative elements and thus provide for simplicity, durability, reliability of action, and adaptability of part replacement.

35 An object is to provide an organization in which each of the parts is of a simple and substantial character.

40 Other objects and advantages will be made manifest in the following specification of an embodiment of apparatus of the invention illustrated in the accompanying drawing; it being understood that modifications, variations and adaptations may be resorted to within the spirit of the invention and the scope thereof as it is here claimed.

Figure 1 is a vertical longitudinal section of the apparatus in a well casing.

45 Figure 2 is a plan of a gas vent head.

Figure 3 is a plan of a foraminous shelf.

Figure 4 is a plan of a gas rejector.

Figure 5 is a plan of a fitting plug.

Figure 6 is an elevation of the plug.

50 A string of the units of this invention is shown attachable to the bottom of a pump barrel or intake B, of any type of pump.

Each intake unit comprises a lower fitting 2 internally threaded at 3 for a shell 4 and

having a shoulder 5 threaded at 6 for an inner tube 7. From the shoulder 5 projects up a neck 8 receiving a ring 9 threaded into a jacket 10.

The fitting 2 may be referred to as a gas rejector. For rejecting gas and allowing oil to flow, down to the space between the shell 4 and the tube 7, the shoulder 5 has a series of downwardly convergent passageways or ports 2^a. Preferably the ports 2^a are in the form of inverted cones. Hence when the liquid, as oil, flows down into the ports and approaches the much constricted bottom outlets, the compressive effect of a liquid upon an entrained gas bubble tends to exclude or, more accurately, express the gas out of the oil stream as it converges toward the outlet of the ports. The rejected gas is therefore free to rise in the well casing or naked hole.

The oil passing into the gas rejector flows down to the bottom of the inner tube 7 and then flows upward under natural pressure or pump action. From the inner tube the oil passes up against a body of interstitial material 12, granular, fibrous or porous enough to allow the oil to flow without detrimental rate of speed.

The function of this material is to break up the oil bags or skins enclosing gas bubbles into smaller gas bubbles and thus effecting a general, closer coalescence of the oil body in the stream flowing up in the apparatus. It is the larger bodies of gas merging, one with another under the valves of a pump which causes the pump to gas bind. By breaking up the gas bubbles that may happen to form in, or enter, the apparatus, a more uniform body of oil stream is obtained for action in the pump, with the obvious advantages of continuous flow.

The breaker medium 12 may be confined with suitable density between foraminous shelves 13, as of wire fabric, in the jacket 10.

Screwed on the upper end of the jacket is a trap head having a chamber 14 the top of which has a series of gas venting ports 14^a surrounding a central trap nipple 15. This nipple 15 has an annular wall 16 around its lower end, which latter is provided with a gas rejector 17 having constricting inlet ports 18 from the bottom of the pocket formed by the wall 16, to the chamber in the fitting 17, into which the nipple 15 opens for

suction. The fitting has a plug bottom 17* which may retain the breaker medium 12 in place.

The function of the wall 16 is to form an upflow surrounding space in the jacket, and a downflow pocket to the second rejector and thus causing a complete reversal of liquid flow over the top or lip of the pocket wall. This reversal tends to throw the entrained 10 gas bubbles on upwardly in their natural floating characteristic. The action of the second rejector 17 is to further squeeze out the entrained gas.

The gas collecting in the trap head 14 vents out of the small parts 14* and freely rises in the well hole.

The parts including and between the bottom fitting 2, and its "anchors" 4—7, and the

trap head 14, organized, constitute one excluding, breaking, separating and venting 20 unit. A series of these assembled, en train, or one only, may be attached at its head 14 to a pump intake, or a barrel B.

Two units are shown (one broken away).

What is claimed is:

Bubble breaking and gas separating means for a well, including a tubular body having an intake screen in its lower end to reduce gas bubbles, a closure on the head of the body having a suction nipple extending down therefrom and having gas escape holes outside of the nipple, and a liquid trap at the bottom of the nipple having conical inlet ports to express gas from the incoming oil to the nipple.

HENRY M. GREEN.
